UNITED STATES PATENT OFFICE.

CHARLES F. PIHLBLAD, OF JERSEY CITY, NEW JERSEY.

SHOCK-ABSORBER.

1,123,794.

Specification of Letters Patent.

Patented Jan. 5, 1915.

Application filed July 2, 1913. Serial No. 777,076.

To all whom it may concern.

Be it known that I, CHARLES F. PIHLBLAD, a citizen of the United States, residing at Jersey City, in the county of Hudson and State of New Jersey, have invented new and useful Improvements in Shock-Absorbers, of which the following is a specification.

The object of this invention is to provide 10 a device for the prevention of sudden and disagreeable shocks such as are due to the sudden or abrupt compression of the springs of automobiles and other vehicles, and to provide a device of this character which 15 shall absorb such shocks without impairing the effectiveness of the vehicle springs.

The device of this invention may be used in any connection where there are two parts having relative movement toward and from 20 each other, and in which it is desirable to absorb the shock resulting from the sudden character of such relative movement, and the invention is not to be limited to use in any particular vehicle or machine.

25 The nature of the invention will appear more fully from the accompanying description and drawings, and will be particularly pointed out in the appended claim.

30 The drawings illustrate the preferred form of device embodying the invention, wherein,

Figure 1 is a side elevation of the device in use. Fig. 2 is an enlarged detail side elevation of the invention. Fig. 3 is a detail 35 end elevation with a part broken away to disclose the means for locking the sections of one part of the device.

For the purpose of illustration I have elected to show my device as it will appear 40 when used in connection with the two parts of a vehicle which move relatively toward and from each other when the wheels roll over uneven ground. These parts are herein shown as the chassis 5 and the springs 6.

45 The device forming the subject matter of the present invention and herein indicated generally by *a*, comprises a member *b* and a member *c* fitted respectively to the chassis and spring and adapted when arranged to 50 coöperate one with the other, to offer resistance to the action of the spring and chassis when these parts move relatively toward each other. The part *c* comprises a base plate 7 suitably fastened to the spring 6 as 55 by the clevises 8-8, draw bars 9-9 arranged to slide in holders or guides 10-10

connected with the base plate and springs 11-11 arranged for offering resistance to the sliding movement of the draw bars in one direction. Heads 12-12 forming the 60 inner ends of the draw bars 9-9 form abutments for the inner ends of the springs 11-11 whose outer ends bear on the end guides 10-10. These heads also carry rolls 13-13 which are arranged so as to have 65 portions of their peripheries projecting beyond the inner ends of the heads 12-12. When the parts occupy their normal positions as shown in Fig. 2, projecting portions of the rolls 13-13 are in mutual contact 70 and are so held by the springs 11-11 which are then under slight tension.

The part *b* is suitably secured as by bolts 14, to the chassis 5. This part *b* has its free end directed between the rolls 13-13 and 75 is longitudinally extensible, whereby to compensate for the variations in distance which usually exists between the chassis and middle portions of springs in vehicles of different types or makes. The part *b* is 80 made up of the upper section 15 and the lower section 16. The said upper section 15 has outwardly extending flanges 17-17 which function as stays for the lower section 16 arranged therebetween. The opposed bearing faces of the sections 15 and 16 are serrated as indicated by 18 in Fig. 3, whereby, to obtain an interlocking effect 85 against longitudinal movement of the sections when the bearing surfaces are arranged one upon the other as shown in the drawings. Suitable locking devices such as bolts and nuts 19, are employed for clamping the sections together as shown in Fig. 3. The bolts pass through a longitudinal slot 90 20 in the lower section 16 and the presence of this slot renders as unnecessary the complete withdrawal of the bolts from the sections when adjusting the member *b* to the size required by the distance between the 95 rolls 13-13 and the chassis 5 when the sections *b* and *c* are arranged as shown in Figs. 1 and 2. The lower end portion of the section 16 is tapered as indicated at 20 and the extremity of such tapered portion normally 100 extends to the point of contact between the rolls 13-13. By virtue of the tapering of the portion 20 slant or inclined surfaces are obtained which operate to move the draw bars progressively in opposite directions as the tapered portion 20 passes between the rolls 13-13. This movement on 105 110

the part of the draw bars has the effect of gradually increasing the tension of the springs 11-11 and since the action on the part of the tapered portion 20 results from 5 relative movement toward each other of the chassis and spring resulting from the wheel receiving a sudden jar, it is manifest that this compression of the springs 11-11 will absorb the shock or jar obtained by the 10 wheel.

What is claimed as new is:

A shock absorber comprising a base plate adapted to be positioned upon the intermediate portion of a spring, guides provided 15 upon the base plate, resiliently held bars slidably mounted in the guides and held

therein against turning movement, rolls journaled at the inner ends of the bars, and a longitudinally extensible member mounted for movement in a direction transversely of 20 the base plate and in a line between the inner ends of the bars said member having a tapered end which is engageable with the rolls, the intermediate portion of the base plate being located in the path of movement 25 of said member.

In testimony whereof I affix my signature in presence of two witnesses.

CHARLES F. PIHLBLAD.
